No. 853,893.

PATENTED MAY 14, 1907.

C. L. MILLER.

CHAIR.

APPLICATION FILED NOV. 24, 1905.

UNITED STATES PATENT OFFICE.

CHARLES L. MILLER, OF BELLAIRE, OHIO.

CHAIR.

No. 853,893.

Specification of Letters Patent.

Patented May 14, 1907.

Application filed November 24, 1905. Serial No. 288,864.

To all whom it may concern:

Be it known that I, CHARLES L. MILLER, a citizen of the United States of America, residing at Bellaire, in the county of Belmont and State of Ohio, have invented certain new and useful Improvements in Chairs, of which the following is a specification, reference being had therein to the accompanying drawing.

10 This invention relates to certain new and useful improvements in chairs, and the invention relates more particularly to a folding or collapsible theater chair.

15 The primary object of this invention is to provide a novel form of chair adapted for use in large auditoriums and I have provided novel means whereby a chair can be easily and quickly collapsed and folded into the floor of the auditorium, whereby a clear 20 floor space can be provided for passage ways for the exit of the audience of an auditorium. To this end, I have constructed a theater chair which can be easily and quickly folded into the floor of a theater in case a rapid exit 25 is to be made by the audience in case of fire or like instance. The chair when folded in the floor of a theater provides a clear floor space which may be used for other purposes, but at any time seating capacity is desired, my 30 improved chairs can be easily and quickly erected to firmly support persons comprising an audience or the like assemblage.

With the above and other objects in view, which will more readily appear as the nature 35 of the invention is better understood, the same consists in the novel construction, combination and arrangement of parts to be hereinafter more fully described and then specifically pointed out in the claims, and 40 referring to the drawings accompanying this application, like numerals of reference designate corresponding parts throughout the several views, in which:—

Figure 1 is a side elevation of my improved 45 chair in an open position, Fig. 2 is a vertical sectional view of the same, Fig. 3 is a side elevation of the chair in a collapsed or folded position illustrating its casing in section, Fig. 4 is a sectional view of the same, Fig. 5 is 50 a detail perspective view of one of the arms of the chair, Fig. 6 is a top plan of the back of the chair, Fig. 7 is a perspective view of the back proper. Fig. 8 is a front elevation of the bottom of the chair seat in a folded posi-

tion. Fig. 9 is a detail view partly in central 55 vertical section of one of the side plates of the chair housing.

To put my invention into practice, I employ a rectangular casing 1, having an upper flanged edge 2. This casing is adapted to be 60 constructed in the floor 3 of an auditorium or room in which my improved chair is to be used. In one end of the casing, I mount two diametrically opposed cleats 4, 4 and adjacent to said cleats is pivotally mounted, as 65 at 5, a chair housing 6. The chair housing is adapted to fold into the casing 1 and is enclosed therein by a two-part hinged lid 7 carried by one of the top flanged edges of the casing. When the chair housing is in a vertical position, it is adapted to rest upon the cleats 4, 4 of said casing.

The chair housing 6 consists of side plates 8, 8, a front plate 9 and a rear plate 10. The side plates 8, 8 are provided with vertically 75 disposed slots 11 and the front edge of the plate 9 is cut away as at 12 in order that access may be had to said slots from the front side of the housing. The front sides 14 of the slots 11 are cut away as at 15 and in said 80 cut away portions are pivotally mounted spring held angular strips 16. The front plate 9 of the housing is slotted as at 17, 17, and in said slot is mounted a semi-cylindrical bar 18 to which is attached the ends of the 85 straps 16 which protrude through the openings 12 of the side plates 8, 8. The bar 18 centrally of its length is provided with a knob 19 in order that the bar may be easily manipulated as will be presently described. 90

In the housing 6 is mounted a cross bar 20 having its ends cut away as at 21, 21. The ends of the cross bar are adapted to travel in the slots 11, 11 of the side plates 8, 8 of the housing 6, and the top edge of the bar is provided with two pierced lugs 22, 22 between 95 which is pivotally mounted a chair seat 23. Secured to the rear face of the bar 20 is a chair back casing 24, the sides of which are cut away as at 25 forming a back rest 26. 100 The sides of the casing 24 are provided with plates 27, 27 and pivotally mounted between the back rest 26 and the plates 27 by pins 28 are arm rests 29, 29. The arm rests are slotted in their underneath faces as at 30, 30, and 105 pivotally mounted in the slotted arm rests by pins 31, 31 are arm supports 32, 32, which are pivotally connected to lugs 33, 33 carried at

the sides of the seat 23. In the back casing 24 is mounted a back 34 carrying a depending yoke 35 and depending pins 36, 36. The back 34 is provided with a hand opening 37 and is retained in the casing 24 by a block 38 which extends through the yoke 35 of the back and prevents it from being entirely disengaged from the casing. The top front edge of the casing is provided with openings 39, 39, the object of which will be presently described.

In Figs. 3 and 4 of the drawings, I have illustrated a chair in a collapsed and folded position and by referring to said figures it will be observed that when the chair is placed within the casing 1, that the two-part lid 7 snugly fits within the casing, entirely closing the same. To set the chair up, the lid 7 is opened and the chair housing 6 swung upon its pivot to a vertical position, until it rests upon the cleats 4, 4. When in a vertical position, the part 7' of the lid 7 is folded under the lid and the lid lowered, as illustrated in Fig. 2 of the drawings, to retain the chair housing 6 in a vertical position. The knob 19 of the bar 18 is now gripped and the bar pulled outwardly causing the straps 16, 16 to move within the cut away portion 15 of the side plates 8, 8, and while the straps are held in this position, the seat 23 and the back casing 24 are elevated to the top of the slots 11, 11. When they have reached this position, the bar 18 is released which permits of the straps 16 assuming their normal position in the cut away portions 21, 21 of the bar 20 thereby supporting said bar in its raised position. The seat 23 is now thrown downwardly, this operation placing the arms in position to be used as a chair. The back 34 is now gripped in the opening 37 formed therein, then elevated and moved forward until the pins 36, 36 are in alinement with the openings 39, 39 formed in the back casing, at which time the back is lowered until the pins 45 enter the openings whereby the back 34 is locked in direct alinement with the back rest 26.

The back plate 10 of the chair casing 6 is cut away as at 40 which permits of the back casing, together with the back 34, being inclined to conform to the natural position of a body when in a sitting position.

To collapse the chair and fold it within the casing 1, the back 34 is elevated until the pins 36, 36 have become disengaged from the back casing, at which time the back 34 is lowered into its casing. The seat 23 is thrown upwardly, the arm supports 32, 32 receding within the slots of the arm rests 29, 60 while the arm rests engage in the cut away portions 25 of the back casing, permitting the seat to be folded against the back casing. The bar 18 is now pulled outwardly to remove the straps 16, 16 from beneath the back casing, at which time said casing descends

into the housing 6. The housing is now folded downwardly into the casing 1, and the lid 7 closed upon said housing.

From the construction of my improved chair, it will be seen that a simple, strong, durable and inexpensive chair is provided which can be easily and quickly collapsed and folded under the floor surface of an auditorium or compartment in which it is used.

The material from which my improved chair is constructed, also the upholstering of the chair, is arbitrary, and such changes in the construction and operation, as are permissible by the appended claims, may be resorted to without departing from the spirit and scope of the invention.

What I claim and desire to secure by Letters Patent, is:—

1. A chair of the character described, comprising a casing having a hinged lid, a chair housing mounted in said casing, a back casing slidably mounted in said housing and provided with a seat pivotally connected thereto, a back movably mounted in said back casing, arms connected to the seat and back casing, means for limiting the movement of the back in its casing, and means carried by the back for engagement with the casing to hold said back in an elevated position.

2. In a folding chair, the combination with a casing adapted to receive the chair in its folded form, and having a hinged lid or cover, of a chair comprising a chair housing having slotted sides, a cross bar mounted for movement in said slotted sides, a chair pivotally connected to said cross bar, means carried by the chair housing for engagement with said cross bar to hold the latter in its elevated position, a back casing telescoping into the chair housing, arms pivotally connected to the back casing, arm supports pivotally connected to said arms and to the seat, a back movable in the back casing, means carried by the back and engaging means located in the back casing for limiting the movement of said back, and means for holding the back in an elevated position.

3. In a folding chair, the combination of a chair housing having slotted sides, a cross bar movable in said slotted sides, a seat pivotally connected to said cross bar, means carried by the front plate of said housing for engagement with said cross bar for holding the latter in an elevated position, a back casing, arms pivoted to said back casing, arm supports pivoted to the said arms and to said seat, a back mounted for sliding movement in the back casing, a loop carried by said back, and a block within the back casing to be engaged by said loop to limit the upward movement of the back in its casing.

4. In a folding chair, the combination with a chair housing, and a seat adapted to slide within the housing, of a back casing also adapted to slide within the housing and

when extended to project above the same, arms pivoted to the back casing, and arm supports pivotally connecting the arms to the chair seat, a back slidably mounted in the back casing, and pins carried by said back to engage with the back casing and hold the back in an elevated position.

In testimony whereof I affix my signature in the presence of two witnesses.

CHARLES L. MILLER.
